United States Patent Office

Des. 224,155
Patented July 4, 1972

224,155

GUITAR BODY OR SIMILAR ARTICLE

Ralph G. Smith, 1420 Georgia St.,
Wichita, Kans. 67216

Filed Dec. 16, 1970, Ser. No. 26,526

Term of patent 14 years

Int. Cl. D17—03

U.S. Cl. D56—1

FIG. 1 is a top, rear and side perspective view of a guitar body or similar article, showing my new design;

FIG. 2 is a front elevational view;

FIG. 3 is a side elevational view, the opposite side being substantially a mirror image thereof; and

FIG. 4 is a rear elevational view thereof.

The bottom, not shown, is flat and unornamented.

I claim:

The ornamental design for a guitar body or similar article, as shown and described.
